Primary Examiner — Cynthia R Underwood*(74) Attorney, Agent, or Firm* — Wolf, Greenfield & Sacks, P.C.(57) **CLAIM**

The ornamental design for a gate hinge cover, as shown and described.

DESCRIPTION

FIG. 1 is a top, front, and right side perspective view of a gate hinge cover according to my new design, the top, front, and left side perspective view being a mirror image thereof; FIG. 2 is a front elevation view thereof; FIG. 3 is a rear elevation view thereof; FIG. 4 is a left side elevation view thereof; FIG. 5 is a right side elevation view thereof; FIG. 6 is a top plan view thereof; FIG. 7 is a bottom plan view thereof; and, FIG. 8 is a bottom, rear, and right side perspective view thereof, the bottom, rear, and left side perspective view being a mirror image thereof.

The dot-dash broken lines represent boundaries of the claimed design and form no part of the claimed design. The dash-dash broken lines depict portions of the gate hinge cover that form no part of the claimed design.
